UNITED STATES PATENT OFFICE.

ISAAC S. LAUBACK, OF BOSTON, MASSACHUSETTS.

SHEET-METAL VESSEL.

SPECIFICATION forming part of Letters Patent No. 317,807, dated May 12, 1885.

Application filed October 7, 1884. (Model.)

To all whom it may concern:

Be it known that I, ISAAC S. LAUBACK, of Boston, (East Cambridge,) in the county of Middlesex and State of Massachusetts, have 5 invented a new and useful Improvement in Sheet-Metal Vessels, of which the following is a full, clear, and exact description.

The invention relates to the securing of bottoms upon or to sheet-metal vessels; and the 10 invention consists, principally, in forming the bottom integral with a flange that forms the support or base of the vessel, and securing the bottom to the open end of the body of the vessel by a lap or folded joint that clinches 15 the body and bottom of the vessel together. The bottom is by preference first made in the 20 form of a basin, then folded or creased to receive the lower open end of the body of the vessel, the fold or crease containing the bottom edge of the vessel being then "upset" to 25 form the joint.

Reference is to be had to the accompanying drawings, forming part of this specification, in 30 which similar letters of reference indicate corresponding parts in all the figures.

Figure 1 is a sectional elevation of the bottom in basin form. Figs. 2 and 3 illustrate the preferred method of creasing the bottom, and Fig. 3 shows also the body of the vessel 35 ready to be placed in the bottom. Figs. 4 and 5 illustrate two methods of upsetting the crease and edge of the body of the vessel to form the joint; and Fig. 6 is a sectional plan view of a completed vessel, taken on the line *xx* of Fig. 4.

a represents the open body of a vessel. *b* represents the bottom of the vessel; *c*, the flange or base, and *d* represents the joint that unites the bottom and body. The bottom 40 *b* is by preference made in the form of a basin—that is, integral with the flange or base *c*, the whole being by preference struck from a suitable blank of sheet metal. The bottom *b* is then creased, as shown at *e*. This may be

done by first depressing the bottom, as shown 45 in Fig. 2, over a hollow tool or mandrel that supports the edge *f* of the bottom, and then elevating the bottom again flush, or nearly so, with the edge *f*, as shown in Fig. 3, a hollow tool or mandrel being used to support the 50 lower edge or fold of the crease *e*. The crease *e* being thus formed, the lower edge of the body *a* will be placed in the crease *e*, as illustrated in Fig. 3, and then both the crease *e* and lower edge of the body of the vessel are 55 overturned or upset either toward the center of the bottom *b*, as shown in Fig. 4, or toward the base *c*, as shown in Fig. 5. The upsetting is done by crushing down or folding over the crease *e* and the lower edge of the body 60 *a*, to form a lip or flange, *a'*, at the lower edge of the body *a*, which will be clinched both above and below by the folding of the crease *e*, so that a perfectly water-tight joint is 65 formed without the use of solder. The upsetting may be done by hand or machinery.

Besides the advantage of forming a watertight joint without the use of solder or rivets, by my invention the vessel is made cheaper and stronger at the bottom than vessels heretofore manufactured, and the support or base 70 *c* is formed solid with the bottom and without extra work.

Having thus described my invention, I claim as new and desire to secure by Letters Patent— 75

1. The combination, with the body, of the bottom *b*, formed integral with the flange *c*, and attached to the body by the folded joint *d*, thus making the vessel with a base complete 80 of two pieces, substantially as set forth.

2. The bottom *b*, made integral with the flange *c*, and having the crease *e* formed in it, substantially as and for the purposes set forth.

ISAAC S. LAUBACK.
